Primary Examiner — Susan E Krakower*Assistant Examiner* — Ramzi Almatrahi*(74) Attorney, Agent, or Firm* — Salter & Michaelson(57) **CLAIM**

The ornamental design for a camera housing, as shown and described.

DESCRIPTION

FIG. 1 is a front elevational view of a camera housing;

FIG. 2 is a left side elevational view thereof;

FIG. 3 is a right side elevational view thereof;

FIG. 4 is a top plan view thereof;

FIG. 5 is a bottom plan view thereof; and,

FIG. 6 is a rear elevational view thereof.

The broken lines depict portions of a camera housing in which the design is embodied and form no part of the claimed design.
